LLOYD B. HUBBARD, OF WICHITA FALLS, TEXAS, ASSIGNOR OF ONE-FOURTH TO BERNARD MARTIN AND BEN G. ONEAL, COMPOSING THE FIRM OF MARTIN & ONEAL, OF WICHITA FALLS, TEXAS.

REVERSIBLE ROTARY MOTOR (GAS).

Application filed July 16, 1923. Serial No. 651,753.

This invention relates to internal combustion engines particularly of the type provided with a rotor having a plurality of radially disposed cylinders in which there are reciprocating pistons carrying rollers which react on an oval track or an eccentrically disposed track to rotate the rotor.

It is an object of the invention to provide an internal combustion engine which will be extremely simple in construction, with a minimum number of parts, will be reliable in operation and not easily gotten out of order, and will also be light in weight in comparison with the power developed.

It is also an object of the invention to provide an engine of this type with improved valve control and ignition mechanism in which the usual cranks, gears, cams and connecting parts are eliminated, further simplifying the construction of the engine and reducing the number of parts required.

It is a further object of the invention to provide an improved means for maintaining the control valve tight so as to prevent leakage, but which will yield to allow for expansion and contraction under changes in temperature incident to operation.

It is a further object of the invention to provide an internal combustion engine of the four cycle type in which there will be an explosion in each cylinder during each revolution of the rotor.

It is another object of the invention to provide a construction in which a more efficient lubrication may be secured with the use of less oil.

It is a still further object of the invention to provide an internal combustion engine which may be easily reversed without the use of gears and the like, and by the shifting of a single element.

It is also an object of the invention to provide a construction in which a single spark plug may be used for all the cylinders, and this plug will be located in the most efficient location for proper ignition.

With the foregoing and other objects in view I have devised the construction illustrated in the accompanying drawing in

which

Fig. 1 is a vertical central section through the engine substantially on line 1—1 of Fig. 2.

Fig. 2 is a transverse section substantially on line 2—2 of Fig. 1.

Fig. 3 is a top plan view of the control valve.

Fig. 4 is a central longitudinal section thereof substantially on line 4—4 of Fig. 3.

Fig. 5 is a transverse section substantially on line 5—5 of Figs. 3 and 4.

Fig. 6 is a transverse section substantially on line 6—6 of Figs. 3 and 4.

Fig. 7 is a transverse section substantially on line 7—7 of Figs. 3 and 4.

Fig. 8 is a transverse section substantially on line 8—8 of Figs. 3 and 4.

Fig. 9 is a transverse section substantially on line 9—9 of Figs. 3 and 4.

Fig. 10 is a longitudinal section through the outer end of a cylinder and a portion of the casing, showing a slightly different construction.

Fig. 11 is a longitudinal section substantially on line 11—11 of Fig. 10, and

Fig. 12 is a longitudinal section through a different form of cooling means.

Referring to the drawings in which similar reference characters are used throughout the various figures to indicate the same elements, the motor includes a stator comprising a casing preferably made of four different elements, two central elements 15 and two side plates 16 and 17. The two central elements 15 are similar, the upper one being inverted and placed on the lower as shown in Fig. 1, and these sections are provided with a central track 18 which is made continuous after the two sections are superimposed, as shown in Fig. 1, upon the surface 19 of which the rollers 20 carried by the reciprocating pistons 21 are run. The pistons are mounted to reciprocate in a plurality of cylinders 22 comprising the rotor. These cylinders as shown in Fig. 1 are equally spaced about the axis of rotation and extend radially from this axis. Any desired number of pistons may be employed but ordinarily I prefer six. The plates 16 and 17 are secured to the opposite sides of the central elements 15 by any suitable means, such as screw bolts 23, and enclose the rotor, as shown in Fig. 2, the elements 15, 16 and 17 providing a closed casing about this rotor.

The shape of the track 18 may vary somewhat, but I prefer to make it substantial, as

shown in Fig. 1, in which the curve from a point A to a point B gradually decreases in radius forming a transition curve. The curve is what I call a two to one curve, that is, the gear feeding the tool for cutting the surface of the track revolves twice to one revolution of the chuck carrying the track. In other words the tool moves in and out twice to one revolution of the track. The elements 15 are provided with any suitable support such as lugs 24 whereby the engine may be mounted on a suitable supporting means 35, and secured thereto by any suitable means such as bolts 26.

15 The plates 16 and 17 are provided with central bearings, these bearings preferably having suitable bushings 27 and 28 respectively in which bearings 29 and 30 of the rotor are mounted to rotate. Extending 20 transversely through the center of the rotor is a tapered bearing opening 31 in which is seated a stationary similarly tapered valve member 32 which controls the flow of combustible gases to and exhaust gases from the cylinders, and the rotor is provided with 25 passages 33 leading from the bearing opening 31 to the inner end of each cylinder. The inner end of each cylinder is preferably concave as shown at 34, as is also the 30 end 35 of the pistons 21 to provide sufficient clearance space to control the amount of compression. The pistons are preferably hollow with circumferential grooves adjacent their ends to receive suitable packing 35 rings 36 to prevent leakage of gases past the pistons in the usual manner. At their outer ends the pistons each carry a transverse sleeve 37 on which are mounted the ball 40 bearings 38 for the rollers 20. Extending through the sleeve 37 is a bolt 39 headed at one end 40 and the other end provided with a nut or washer 41 which is secured to the bolt. The cylinders 22 are provided adjacent their outer ends with slots 42 through 45 which the bolt 39 extends, and mounted on this bolt within the slot are suitable rollers 43. The cylinders are also provided with slots 44 through which the track 18 extends so that during certain portions of the revolution of a cylinder it will straddle this track and help to maintain the stator and the rotor in proper alignment. When the engine is running centrifugal action will ordinarily tend to force the pistons outwardly and retain the rollers 20 in contact with the surface of the track, but unless some other means is provided to prevent it, the upper pistons will drop inwardly toward the center when the engine is stopped. This action 50 may be prevented in various ways one of which is to provide a coiled spring 45 about the cylinder resting at its opposite ends in cup-shaped rings 46, the inner one of which bears against a shoulder at the inner end of the cylinder and the outer one bears against

the projecting ends of the bolt 39 and thus tends to force the piston outwardly. To eliminate these moving springs, however, I may extend the pistons beyond the track as shown at 47 in Figs. 10 and 11 and mount 70 small rollers 48 in these projections to engage shoulders 49 on the opposite sides of the track. By this construction, during ordinary running the rollers 48 have no function but come into play merely when the engine is stopped to prevent the upper pistons dropping inwardly toward the center of the rotor. In this construction, however, the bolt 50 corresponding to the bolt 39 is preferably not extended through the sides of the 75 cylinders although it may be so extended if desired to prevent the piston turning in the cylinder. The long bolt is not necessary, however, as the projections 47 on opposite sides of the track prevent the piston turning. 80 The specific construction of the control valve is clearly disclosed in Figs. 2 to 9. As stated above its outer surface 51 is tapered to correspond with the tapered bearing opening 31 in the rotor and it forms a 85 close bearing fit therewith. As will be apparent from these figures this member is provided in its outer wall with two recesses 52 and 53 on opposite sides of a separating wall 54, and there are two longitudinally 90 extending passages 55 and 56 leading to these recesses respectively. These passages lead at their outer ends to lateral openings 57 and 58 respectively in an oppositely tapered portion 59 of the valve member, which 95 openings may communicate with gas inlet and exhaust passages 60 and 61 respectively. The recesses 52 and 53 are so located 100 on the valve member as to come successively in alignment with the passages 33 leading 105 to the inner ends of the cylinders as the cylinders rotate about the valve member. For the purposes of this description I will call 60 the inlet passage and 61 the exhaust 110 passage, but they may obviously be reversed if desired. Between the two tapered portions 51 and 59 is a flange 62 provided with one or more openings 63 through which extend bolts or studs 64 carried by the plate 115 16, and carried by this flange are one or more studs 65 extending through curved slots 66 in the flange 67 of a valve sleeve 68. This sleeve is internally tapered to fit the taper of the portion 59, and externally tapered to fit a corresponding taper in a fitting 69 having the inlet and exhaust passages 60 and 61, a suitable inlet pipe not shown being connected to the inlet 60 to lead a combustible mixture to the fitting from a suitable carburetor, and a suitable conducting pipe being lead from the exhaust 120 61 to any suitable point of discharge, as into a muffler. The studs 65 also extend through suitable lugs 60 on the fitting 69 and these studs are threaded at their outer 125 130

ends to receive suitable nuts 71. They are also of such a length that springs 72 may be inserted on these studs between the nuts and the lugs 70. The sleeve 68 is provided with 5 two diametrically disposed openings 60' and 61' which are adapted to register with the openings 57 and 58 for the purpose of controlling the direction of rotation of the rotor in the manner presently to be described. To 10 facilitate shifting of the valve sleeve 68 the flange 67 thereof may be provided with a suitable handle 73.

On the opposite side of the valve member 15 from the separating wall 54 and the recesses 52 and 53 is a passage 74 leading through the side wall of the valve member, and it is also so located as to communicate with the 20 passages 33 successively as the rotor rotates about the valve member, but it is out of communication with the passages 55 and 56. At its inner end this passage leads to a threaded boss 75 adapted to receive a spark plug shown in dotted lines in Fig. 2, the sparking 25 points of this plug being in the passage 74, and the body of the plug lying in the passage 77 leading to the outside of the valve member. The lead wire for the spark plug is lead thereto through the inlet opening of this passage, if the plug is not of 30 sufficient length to extend to the outer side of the flange 62.

Leading longitudinally into the valve member 32 from its smaller end is an oil passage way 78, and on opposite sides of the 35 passage 74 are two passage 79 leading to a circumferential groove 80 in the outer wall of the opening 31.

The rotor is provided with circulating 40 passages 81 leading from this groove to the opposite side of the rotor where they discharge into the casing outside of the cylinders as shown at 82 in Fig. 2. If preferred the groove 80 may be formed in the valve member instead of the rotor, as will be obvious.

At the inner or smaller end of the tapered valve member 32 the rotor is provided with a cylinder 83 in which a piston 84 may reciprocate, this piston being secured to the 50 valve member by any suitable means such as screw threads, and the piston has in its periphery one or more grooves to receive suitable packing 85 to make a tight fit with the walls of the cylinder. Secured to the 55 rotor beyond this piston and covering the end of the cylinder is a shaft 86 which has a flange 87 secured to the rotor by any suitable means such as bolts 88. This shaft leads to any suitable power transmitting 60 means, such as a pulley or gear, to transmit power from the rotor to a place of use. The bolts 88 and the end of the shaft are enclosed by cap 89 leaving a space 90, and the flange of the shaft is provided with 65 sages 91 leading to the cylinder 83. The

cap 89 closely embraces the shaft 86 and is provided with a groove to receive suitable packing 92 to prevent leakage of oil about the shaft. Leading from the outer portion of the casing, as shown in Fig. 2, 70 to the space 90 is one or more conducting pipes 93 to conduct the cooling fluid from the casing back to this space, as will presently be described. If desired these pipes 75 may be provided with a series of heat radiating fins 94, or if preferred, as shown in Fig. 12, they may be enclosed in a jacket 95 through which a cooling fluid such as water may be circulated. The inlet and outlet passages to this jacket are shown at 96 80 and 97 respectively.

For the purpose of lubricating the outer walls of the tapered portion 51 and the bearing opening 31 a series of openings 98 are provided in the separating wall 54 communicating with an oil passage 99, leading from the passage 78 to conduct oil to these surfaces.

For the purpose of lubricating the bearings 29 and 30 of the rotor, and the bushings 27 and 28, oil passages 100 lead from the casing to oil grooves 101 in these bushings.

The operation is as follows: With the elements in position as shown in the drawings 95 with 60 used as the inlet for combustible gases (the valve element being inverted in Figs. 8 and 9 from the position shown in Figs. 1, 2, 3, and 4) the rotor will rotate counter clock-wise as shown in Fig. 1, or 100 in the direction of the arrow. The cylinder C is shown on the inlet stroke, the cylinder D at the beginning of the compression stroke, the cylinder E approaching the end of the compression stroke and the point of ignition, the cylinder F on the explosion or working stroke, the cylinder G at the end of the explosion stroke and about the beginning of the exhaust stroke, and the cylinder H in the exhaust stroke and approaching 105 the end thereof. With the valve in position, as shown in Fig. 1, the position of the spark plug is shown in dotted lines, and the ignition passage 74 comes into communication 110 with the passage 33 of a cylinder just before the cylinder passes through the vertical central line A—A. The spark may be controlled by the conventional timing mechanism having the usual means for advancing and retarding the spark, or if preferred the spark may be made continuous as the passage 74 is in communication with the cylinders only at the end of the compression stroke and the beginning of the explosion 115 stroke.

If it is desired to reverse the engine all that is necessary is to shift the valve sleeve 68 to shift the openings 60' and 61' therefrom in the positions shown in Fig. 9 where they are in communication with the pas- 120 130

- 4
- sages 56 and 55 respectively to the left or counter clock-wise, as viewed in this figure, to bring these openings respectively into communication with the passages 55 and 56.
- 5 Thus the passage 55 will then be in communication with the inlet 60 for the combustible gases and the passage 56 will be in communication with the outlet 61 for the exhaust gases. It will be apparent that by shifting the valve member 32 about its axis the point of ignition may be varied as desired, and thus by shifting the valve member the spark may be advanced or retarded without the use of a timing mechanism.
- 10 The path of circulation of the cooling medium will now be described. This medium is preferably oil and the space in the casing surrounding the cylinders is filled with this oil. It will be apparent that as the rotor rotates centrifugal action will tend to throw this oil toward the outer edge of the casing, and the pressure will thus be greater against the outer edge of the casing. This pressure will force the oil into the 15 conducting pipes 93 by which it will be conducted to the space 90. It will flow from this space to the passages 91 to the cylinder 83, then to the passage 78 in the valve member from which it will pass through the 20 passages 79 to the groove 80 and from this groove through the circulating passages 81 back to the casing. The path of circulation is shown by the arrows in Fig. 2. This cooling medium will cool the cylinders and 25 the valve element and will itself be cooled in the pipes 93. It will at the same time lubricate all the moving elements and there will be a forced feed of oil through the openings 98 to the bearing surface between 30 the valve member and the rotor. The number of oil cooling and conducting pipes 93 may be made as found desirable and as required for proper cooling of the oil.
- 35 The piston 84 connected to the valve member 32 will tend to move this member longitudinally of its axis and to the left as viewed in Fig. 2, to hold the valve in close contact with the bearing opening in the rotor. This is because the bearing between 40 this piston and the passages 33 may be sufficiently loose to allow leakage of gases under pressure from these passes to the right hand side of the piston as viewed in Fig. 2. Thus the pressure between the valve member 45 50 55 60 65 70 75 80 85 90 95 100 105 110 115 120 125 130
- 55 and the rotor would be maintained sufficiently tight by the action of the gases to prevent leakage. If preferred one or more gas passages 84' may be provided leading to the cylinder 83 to conduct the gas pressure to the piston 84. It will be noted that as the cylinder 83 and the piston 84 are located in the rotor the reaction between the rotor and the valve member are wholly in the rotor so that there is no side thrust on the rotor and no thrust bearing is required. By this

means of retaining the valve tight the pressure between the valve member and the rotor is always automatically controlled according to running conditions and the valve will automatically shift to accommodate expansion and contraction due to changes in temperature incident to running conditions. It will also automatically adjust itself to compensate for wear. If the engine is stopped there is nothing tending to bind the valve in its bearing so that when the engine is again started there will be no trouble of this valve sticking.

It will also be apparent that the engine is extremely simple in construction requiring a minimum number of parts, that the lubrication is practically a forced lubrication without requiring the use of a separate pump, and that the usual cranks, gears, cams, camshafts and so forth of the ordinary internal combustion engines are eliminated. The reversing mechanism is extremely simple, and the cooling system has a positive circulation. It will also be apparent that a single spark plug may be used for firing all the cylinders in succession, and that it may be located in the most efficient position. As the spark plug is in communication with a cylinder only for a short time a separate timing mechanism is not necessary and a continuous spark may be employed. It is also to be noted that there is an explosion in each cylinder in every revolution so that with a six cylinder engine there will be six explosions during each revolution of the rotor. Because the piston makes two reciprocations in one revolution of the rotor it will be apparent that its speed for a given rate of rotation of the rotor is twice that of the pistons of the ordinary four cycle engine for the same speed. This tends to greater efficiency as it gives a greater piston speed for a given speed of the engine. Another important feature of this engine is that the combustible mixture is fed to the cylinders at their inner ends, and therefore, the centrifugal action on these gases will assist the suction of the piston in drawing the combustible mixture into the cylinder. In other words, in this type of engine, for a given capacity of cylinder there will be a larger amount of combustible gases drawn into the cylinder than will be the case in the corresponding size of cylinder of the ordinary four cycle engine. This gives greater power for a given cylinder capacity.

Having thus set forth the nature of my invention what I claim is:

1. In an internal combustion engine, a closed casing, a rotor in said casing having a plurality of radially disposed cylinders, reciprocating pistons in said cylinders, means in the casing coating with said pistons to rotate the rotor, said rotor being

- provided with a central transverse bearing opening and fluid passages leading from said opening to said cylinders, a valve member in said opening provided with inlet and 5 exhaust passages adapted to communicate with said fluid passages as the rotor rotates, an ignition device carried by the valve member and adapted for communication with the cylinders, means for conducting 10 explosive gases to the valve member, means for conducting exhaust gases from the valve member, and manually controlled means for at will connecting the explosive gas conducting means to the inlet passage in the 15 valve member and connecting the exhaust gas conducting means to the exhaust passage in the valve member, and also to reverse these connections.
2. In an internal combustion engine, a 20 closed casing, a rotor in said casing having a plurality of radially disposed cylinders, reciprocating pistons in said cylinders, means in the casing coacting with said pistons to rotate the rotor, said rotor being 25 provided with a central transverse tapered bearing opening and fluid passages leading from said opening to said cylinders, a valve member provided with a tapered portion seated in said opening and provided with inlet and exhaust passages 30 adapted to communicate with said fluid passages as the rotor rotates, said valve member being provided with a second tapered portion outside the rotor provided with lateral openings communicating with the inlet and exhaust passages, a tapered sleeve on said latter tapered portion having openings adapted for communication with those in the tapered portion, a fitting embracing 35 said sleeve and having a supply passage 40 for combustible gases and a passage for exhaust gases, a flange between the tapered portions of the valve member, springs carried by the flange tending to hold the fitting, sleeve and valve member in engagement, and means for shifting the sleeve about the valve member.

In testimony whereof I affix my signature.

LLOYD B. HUBBARD.
